United States Patent Office

Des. 222,270
Patented Oct. 12, 1971

222,270

COMMUNICATION APPARATUS

Donald Michael Genaro, Haworth, N.J., and Carl Paul McFadden, Federal Heights, Colo., assignors to Bell Telephone Laboratories, Incorporated, Berkeley Heights, N.J.

Filed July 16, 1970, Ser. No. 33,903

Term of patent 14 years

Int. Cl. D14—03

U.S. Cl. D26—14

FIG. 2

FIG. 3

FIG. 4

FIG. 1 is a perspective view of our new design for communication apparatus;

FIG. 2 is a top view of the communication apparatus;

FIG. 3 is a front view of the communication apparatus; and

FIG. 4 is a side view of the communication apparatus, the opposite side being essentially a mirror image thereof.

The undisclosed rear side of the communication apparatus is plain and unornamented.

We claim:

The ornamental design for communication apparatus, substantially as shown and described.
